[57] CLAIM

The ornamental design for a luggage case, substantially as shown and described.

DESCRIPTION

FIG. 1 is a perspective view of a luggage case showing our new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof;

FIG. 8 is a front perspective view similar to FIG. 1, but showing the luggage case with its end portions expanded, and with a carrying strap attached to the case; and

FIG. 9 is a rear elevational view of the luggage case shown in FIG. 8.
